B. C. STICKNEY

TYPEWRITING MACHINE

Filed May 12, 1921.

Inventor:

Durham & Stickney

UNITED STATES PATENT OFFICE.

BURNHAM C. STICKNEY, OF ELIZABETH, NEW JERSEY, ASSIGNOR TO UNDERWOOD TYPEWRITER COMPANY, OF NEW YORK, N. Y., A CORPORATION OF DELAWARE.

TYPEWRITING MACHINE.

Application filed May 12, 1921. Serial No. 468,822.

To all whom it may concern:

Be it known that I, BURNHAM C. STICKNEY, a citizen of the United States, residing in Elizabeth, in the county of Union and State of New Jersey, have invented certain new and useful Improvements in Typewriting Machines, of which the following is a specification.

This invention relates to typewriting machines adapted for use in preparing stencil or other cards, and is in the nature of an improvement on the patent to J. A. B. Smith, No. 1,219,598, dated March 20, 1917.

In said patent, each card was placed in a holder and was line-spaced by means of suitable racks connected with the holder and meshing with pinions or gears fixed on the platen-axle, which was actuated for line-spacing by the usual line-spacing mechanism of the Underwood standard typewriter.

According to the present invention, the card-holder may be connected with racks meshing with toothed members, preferably in the form of sectors, fixed on the platen-shaft.

To line-space the platen-axle, an arm fixed thereto may be connected by suitable means, such as a link, to a lever pivoted on the platen-frame. Control of the lever may be effected by suitable means, such as a double pawl, pivoted on the lever, and a stationary toothed member, with which the teeth of said pawl will engage alternately, whereby actuation of the lever in line-spacing action will be limited to step-by-step movement, but movement in the opposite direction may be continuous throughout the range of movement of the lever.

The platen may be loose on its axle, and means may be provided whereby the platen will normally be held against rotation, but will be given a slight movement under certain conditions. Such means may comprise a ratchet-wheel and a link, connecting said ratchet-wheel with one end of the platen, so that the latter may be controlled by the former. Normally, the ratchet-wheel will be held stationary by a suitable detent, but, upon a downward movement of the card-holder, the ratchet-wheel may be actuated by a pawl on the holder, thereby slightly rotating the platen. This rotation of the platen is herein referred to as a creeping

movement because it is of relatively slight extent as compared with the entire movement of the work-holder.

Other features and advantages will hereinafter appear.

In the accompanying drawings,

Figure 1 is a fragmentary plan view of the platen-frame of an Underwood standard typewriter, with the invention applied thereto.

Figure 2 is a vertical section, taken along the line 2-2 of Figure 1, looking in the direction of the arrows, and shows the parts in the positions assumed when the card-holder is in its upper limiting position.

Figure 3 is a view similar to Figure 2, but showing the parts in the positions assumed when the card-holder is in its lower limiting position.

Figure 4 is a fragmentary perspective view, showing a card supported in the holder in front of a short platen, in position to enable typing to be effected on the card.

A short platen 1 is loosely mounted on an axle or shaft 2, which is journaled in the ends 3 and 4 of a platen-frame 5, forming part of a carriage 6, slidably mounted on a frame 7. Preferably, the platen 1 is held against movement longitudinally of the axle 2 by means of collars 8 fixed to said axle, and the axle itself is held against longitudinal movement with reference to the platen-frame by means of collars 9 fixed to the axle outside of the ends 3 and 4 of the platen-frame.

A card 10 which may be a stencil-card comprising stencil material stretched across a frame 11 of pasteboard or other suitable material, may be inserted so that its lower edge enters pockets or hooks 12 at the lower ends of fingers 13 secured at the upper ends to a bar 14. Provision may also be made of spring-fingers 15 attached to fingers 13, and bent over said bar 14 and downwardly into position to engage the upper edge of the card 10 to hold the same in position relative to the platen. It will be seen that the structure just described constitutes a holder.

At its ends, the bar 14 is connected to the upper ends of racks 16, which mesh with gear-members 17 in the form of sectors fixed on the axle 2. The racks 16 are held in engagement with the sectors 17 by flanges 18

2
 turned outwardly from plates 19 pivoted on the axle 2, the plates being held against movement longitudinally of the axle 2 by means of collars 20 fixed thereon. The frame, composed of bar 14 and racks 16 secured to its ends, may also be guided by pins 21 extending outwardly from the ends of the frame and projecting into cam-slots 22 in plates 23 fixed on the top of the platen-frame.

It will be noted that each cam-slot 22 comprises a vertical portion merging into a forwardly-directed cam-portion, which continues into a rearwardly and downwardly directed portion. Thus the fingers 13 and racks 16, in the first part of their travel, move downward substantially in straight lines, but when the pins 21 enter the forwardly-curved portions of the cam-slots, said fingers 13 and racks 16 are swung so as to carry their lower ends rearwardly to avoid striking portions of the machine frame which lie in their original path. Slight rearward curving of the cam-slots 22 at their lower ends serves to guide the holder, to properly present the card to the platen surface. It will also be noted that the flanges 18 of the pivoted retaining plates 19, by holding the racks in mesh with the gear-members 17 throughout the reciprocating movement, serve to maintain the relation of the fingers 13 to the platen surface, so as to hold the card carried by said fingers, in operative position with reference to the platen.

35 The line-spacing mechanism for axle 2, and, consequently, for the card-holder, may comprise a lever 24, which, when actuated, will thrust rearwardly a link 25, suitably pivoted thereto, to move an arm 26, fixed on the axle 2, to which the link is pivoted at its rear end. The lever 24 swings about a pivot 27, preferably in the form of a shouldered screw, by which the lever is supported on a plate 28 secured to the platen-frame in any suitable manner. Movement of the lever in opposite directions may be limited by means of a pin 29 on plate 28, the limiting positions of the lever being indicated in full and in dot-and-dash lines in Figure 1.

50 The plate 28 is provided with ratchet-teeth 30 in an arc of a circle about pivot 27, and pivoted on lever 24 is a double pawl 31 comprising teeth 32 and 33 and a handle 34, the double pawl normally being held in position, with the tooth 32 engaging a ratchet-tooth 30, by means of a spring 35 fixed to the lever 24, and movement of the handle 34 by the spring being limited by a pin 36. When it is desired to line-space the card-holder, 55 the handle 34 is moved against the action of the spring 35 to release the tooth 32 from the tooth 30, and then the handle 34 is advanced with the lever 24 until the latter is checked by engagement of the tooth 33 with another tooth 30. It will be evident that,

upon lifting the tooth 32 out of engagement with the tooth 30, the tooth 33 will be so positioned that, upon movement of the lever 24 through one space, the tooth 33 will engage a tooth 30 to prevent further movement. Upon releasing handle 34, the tooth 33 will be withdrawn and the tooth 32 again moved into engagement with a tooth 30 by means of the spring 35. This operation must be repeated for each line-space movement of the lever 24 and consequently of the card-holder, but, after reaching its final position shown in dot-and-dash lines in Figure 1, the lever 24 may be restored to its normal left-hand position by a single movement. It will now be evident that the card-holder may be raised step by step by means of the lever 24 and handle 34, and that it may be returned to its lower limiting position by swinging the lever 24 to the left, Figure 1, or by merely forcing down the card-holder.

According to the present invention, the platen is normally held stationary. To this end, a link 37 is connected by a pivot 38 to one end of the platen 1, and at the other end, by means of a pivot 39, to a ratchet-wheel 40 rotatable about a stud or pivot 41 on a bracket 42 secured to the platen-frame. Normally, the ratchet-wheel 40 is held against operation by means of a pin 43 engaging between successive teeth thereof, the pin 43 being carried by an arm 44 pivoted at 45 on bracket 42 and urged toward the ratchet-wheel 40 by means of a spring 46.

It is desired, however, for the purpose of rendering the wear more uniform, to cause the platen 1 to creep from time to time to present new portions of the surface to the types 47 which are swung into engagement therewith by type-bars 47a. To this end, a pawl 48 is pivoted at 49 on a bracket 50 carried by the bar 14, and the pawl 48 is urged rearwardly by a spring 51 to a limiting position, in which a pin 52 on the pawl 48 engages the upper edge of the bracket.

It will be evident that, during the greater part of the movement of the holder, the platen will be held against rotation, but, upon downward movement of the holder from its upper position, indicated in Figure 2, a tooth 53 of the pawl 48 will engage a tooth of the ratchet-wheel 40, and cause a slight rotation of the latter, and consequent creeping of the platen 1. From inspection of Figures 2 and 3, it will be seen that the platen will be caused to creep step by step in a counter-clockwise direction from the position shown in Figure 2 to that shown in Figure 3, and then it will be caused to creep step by step in the opposite direction until it again assumes the position shown in Figure 2. Ordinarily, the holder will be moved from the Figure 2 position to the Figure 3 position by pressing downwardly thereon, such movement being accompanied by a

movement of the lever 24 from the dot-and-dash line position shown in Figure 1 to that shown in full lines, but such downward movement of the holder may also be effected by swinging the lever 24 to the left from the dot-and-dash line position to the full-line position in Figure 1.

Variations may be resorted to within the scope of the invention, and portions of the 10 improvements may be used without others.

Having thus described my invention, I claim:

1. In a typewriting machine, in combination, a rotatable platen, a work-holder, 15 means for feeding said work-holder past the printing line, and normally ineffective means effective upon a return movement of said holder to cause the platen to creep.

2. In a typewriting machine, in combination, a normally stationary rotatable platen, a work-holder, means for feeding 20 said work-holder past the printing line, and means whereby the work-holder, during a minor portion of its movement only, will cause the platen to creep.

3. In a typewriting machine, in combination, a normally stationary platen, a card-holder, and means actuatable by the insertion 30 of a card to a position to receive the first line of writing, to cause the platen to creep.

4. In a typewriting machine, in combination, a normally stationary platen, an axle 35 on which said platen is loosely mounted, work-feeding means connected to said axle, means to turn forward said axle step by step to feed the work and to return the axle in one movement, controlling means for said platen, and means whereby the turning means, in its return movement, will cause the platen to creep.

5. In a typewriting machine, in combination, a normally stationary platen, an axle 45 on which said platen is loosely mounted, a work-holder connected with said axle, so as to be actuatable thereby, a pawl on said work-holder, and means actuatable by said pawl for causing said platen to creep when said work-holder is moved to a position to receive the first line to be written.

6. In a typewriting machine, in combination, a normally stationary platen, an axle 55 on which the platen is loosely mounted, a work-holder connected with said axle for actuation thereby, a toothed wheel adjacent one end of the platen, a link connecting said wheel to said end of the platen, and a pawl on said work-holder, which, during the movement of the latter to a position for starting typing on a work-sheet, will actuate said wheel and consequently cause said platen to creep.

7. In a typewriting machine, in combination, a platen, a platen-axle, and means 65 to actuate the latter, comprising a pivoted

lever, a double pawl pivoted on said lever, normally positioned with one of its teeth engaging one of the teeth of a fixed segment, so as to prevent line-spacing by said lever, and a handle for said double pawl, 70 upon movement of which the tooth of the pawl formerly in engagement with the tooth of the segment will be withdrawn, to enable the lever to be advanced to line-space the platen-axle, the movement of said handle 75 being effective to move the other tooth of the double pawl into engagement with another tooth of the segment, to prevent movement of more than one step at a time.

8. In a typewriting machine, in combination, a normally stationary platen, an axle 80 on which the platen is loosely mounted, a card-holder movable past the printing line in both directions, a connection between the holder and said axle, and operating means 85 for said axle, comprising a lever and controlling means for said lever, whereby the lever will be prevented from moving more than one step at a time in a line-spacing direction, but may be returned to its starting 90 position in one movement.

9. In a typewriting machine, in combination, a normally stationary platen, an axle 95 on which the platen is loosely mounted, a card-holder movable past the printing line in both directions, a connection between the holder and said axle, operating means for 100 said axle comprising a lever, controlling means for said lever, whereby the lever will be prevented from moving more than one step at a time in a line-spacing direction, but may be returned to its starting position in one movement, and means whereby, upon 105 a return movement of the lever, the platen will be caused to creep.

10. In a typewriting machine, in combination, a platen, an axle on which the platen is loosely mounted, a card-holder movable past the printing line in both directions, a 110 connection between the holder and said axle, operating means for said axle, comprising a lever, controlling means for said lever, whereby the lever will be prevented from moving more than one step at a time in a line-spacing direction, but may be returned to its starting position in one movement, controlling means normally holding the platen 115 stationary, and means whereby, in said return movement of the lever, the controlling means will be actuated to cause said platen to creep.

11. In a typewriting machine, in combination, a normally stationary platen, a work-holder, means for feeding said work-holder past the printing line, and means whereby 125 the work-holder, during a short portion of its movement only, will effect a creeping of the platen.

12. In a typewriting machine, in combination, a normally stationary platen, a card- 130

holder, a lever, controlling means therefor, permitting step-by-step movement in one direction to different positions and permitting continuous movement in the opposite direction, and connections between said lever and said card-holder, whereby each position of said lever will correspond to a line-space position of said card-holder, said controlling means for said lever being adapted to yield upon downward movement of said holder and to permit the lever to be returned to its normal position.

13. In a typewriting machine, in combination, a normally stationary platen, a card-holder, feeding means to advance said holder step by step and to return it in one movement, and means whereby said feeding means, in its return movement, will cause a creeping of the platen.

14. In a typewriting machine, in combination, a normally stationary platen, a work-holder associated therewith, feeding means to line-space said holder past the printing line and return the same to normal position, a pawl, and means whereby said pawl will be actuated during the return movement of the work-holder to effect a creeping of said platen.

15. In a typewriting machine, in combination, a normally stationary platen, a work-holder, means to line-space the work-holder comprising a pivoted lever, a double pawl pivoted on said lever normally positioned with one of its teeth engaging a tooth of a fixed ratchet segment, so as normally to prevent line-spacing by said lever, a handle for said double pawl, upon movement of which the tooth of the double pawl, formerly in engagement with a tooth of the segment, will be withdrawn, to enable the lever to be advanced to line-space the work-holder, the movement of said handle being effective to move the other tooth of the double pawl into engagement with another tooth of the segment, to prevent movement of more than one step at a time, and means whereby a return movement of said lever will effect a creeping of said platen.

16. In a typewriting machine, in combination, a work-holder, an operating lever connected to the work-holder to advance and return therewith, and means co-acting with the lever to compel its advance to be made progressively in successive stages, each stroke being a single line-space in extent, but permitting the lever to be returned in the opposite direction to initial position, with the work-holder, in a single uninterrupted stroke.

17. In a typewriting machine, in combination, a normally stationary platen, a work-holder movable past the printing line in both directions, a lever connected with said work-holder, so that movement of one will effect movement of the other, detent means to

70 maintain said lever and work-holder in different line-space positions, means to limit the movement of said lever and holder in both directions, and means whereby, upon return movement of said lever and holder, 75 creeping of the platen will be effected.

18. In a typewriting machine, in combination, a rotatable platen, a work-holder, means for feeding said work-holder past the printing line, controlling means for said platen normally holding the same stationary but effective, when actuated successively, to move said platen step by step in one direction until a limiting position is reached, and then to move it step by step in the opposite direction until the opposite limiting position is reached, and means whereby said holder, upon each of its return movements, will actuate said platen to give it a single step 80 85 creeping movement.

19. In a typewriting machine, in combination, a rotatable platen, a work-holder, means for feeding said work-holder past the printing line, comprising a ratchet-wheel, a detent therefor, and a link pivoted to said platen and to said ratchet-wheel, whereby said platen will normally be held stationary, but, upon step-by-step actuation of said ratchet-wheel, said platen will be caused to creep step by step in one direction during a half rotation of the ratchet-wheel, and during the next half rotation thereof will be caused to creep in the opposite direction, and means whereby said ratchet-wheel will be actuated each time said work-holder is given a return movement from its final to its initial position.

20. In a typewriting machine, a platen, a work-holder for advancing the work in a line-feed direction without moving the platen, and means for operating the work-holder to line space the work and for causing the platen to creep after a plurality of line-spacing movements of the work-holder.

21. In a typewriting machine, a work-holder, a platen, line-spacing means for causing the work-holder to line-space the work, mechanism for causing the platen to creep, and means normally in an inoperative position but movable, by a plurality of operations of the line-spacing means, into position to operate the platen-creeping mechanism.

22. In a typewriting machine, a platen normally stationary during feeding of the work, and work-feeding means normally operatively disconnected from the platen but movable into position to cause a creeping of the platen.

23. In a typewriting machine, in combination, work-feeding means, an operating handle connected to move the work-feeding means in opposite directions between fixed extreme positions, and means to compel the handle in its progress from one extreme po-

sition to the other for feeding the work to be advanced, from point to point, in separate stages.

24. In a typewriting machine, a platen, 5 a lever, and means for transmitting movement of the lever to the platen arranged to move the platen in one direction upon a movement of the lever, and to move the

platen in the opposite direction upon a subsequent movement of the lever in the same 10 direction.
